United States Patent Office

Des. 221,305
Patented July 27, 1971

221,305

TELEVISION CAMERA OR SIMILAR ARTICLE

James W. Fitzgibbons, Palo Alto, and Kellogg Fleming and Gene Tepper, San Francisco, Calif., assignors to Sylvania Electric Products Inc.

Filed June 29, 1970, Ser. No. 23,745

Term of patent 14 years

Int. Cl. D14—03

U.S. Cl. D61—1

FIG-1

FIG-3

FIG-2

FIG. 4

FIG. 5

FIG. 1 is a perspective view of a television camera or similar article showing our new design;

FIG. 2 is a front elevational view thereof; and

FIG. 3 is a left side elevational view of FIG. 2 as taken from lines 3—3; and

FIG. 4 is a top plan view thereof; and

FIG. 5 is a rear elevational view of FIG. 4 as taken from lines 5—5.

We claim:

The ornamental design for a television camera or similar article, as shown and described.
